UNITED STATES PATENT OFFICE.

JOHANN A. H. MEYER, OF DRESDEN, SAXONY, GERMANY.

CUTTER FOR PAPER, CLOTH, &c.

SPECIFICATION forming part of Letters Patent No. 276,265, dated April 24, 1883.

Application filed November 13, 1880. (No model.) Patented in Germany June 18, 1880, No. 12,712; in England October 26, 1880, No. 4,364; in Luxemburg October 27, 1880, No. 85; in Belgium October 30, 1880, No. 52,906; in Austria-Hungary December 14, 1880, No. 34,437 and No. 38,476, and in Italy December 31, 1880, XXIX, 432.

To all whom it may concern:

Be it known that I, JOHANN AUGUST HEINRICH MEYER, residing at Dresden, in the Kingdom of Saxony, Germany, have invented certain new and useful Improvements in Cutters for Paper, Cloth, &c., of which the following is a specification.

The accompanying drawings form a part of this specification and illustrate the invention. 10 Figure 1 is a front view. Fig. 2 is a cross-section taken on line xx , Fig. 1, and having the levers and link removed.

Two upright pillars or frames on a horizontal base-plate are provided with two guides in 15 an oblique position, in which the knife-beam h , with the knife o , may be moved up and down.

The mechanism for moving the beam h and knife o up and down consists of a lever, i , which 20 is pivoted at the left-hand pillar at x . Lever i and beam h are connected by rod k . The free end of the lever i is traversed by a pin or bolt, q , forming the pivot for lever f . The boss of this lever is partly furnished at its periphery 25 with teeth taking into the teeth which are formed at the upper end of the pillar or frame r . These teeth on pillar or frame r constitute a fixed or standard wreath of teeth of an elliptical form. As the teeth on the boss of the 30 lever f are arranged eccentrically to the center of motion q , as shown in the drawings, it follows that if this lever f is turned from the position shown (at the left side) into the opposite position (to the right side) the motion 35 of part $i k h$ will, in consequence of the proportions of parts or of transmission, be a rapid one in the beginning, decreasing toward the end of the motion of the lever f , whereby the cutting of the knife o through a layer of cloth, 40 paper, &c., put underneath the press-beam e will be accomplished with ease. The presser-beam e has attached to its lower edge, at either end, the arms d , which extend down through openings in the table and are pivoted 45 to the rod e' . The lever $d' c$, pivoted at one end to the bar e' and fulcrumed at a proper point in its length to a stud projecting beneath the table, is attached to the lower end of a screw-rod, a , with the top of which, above the 50 table, a hand-wheel, b , engages. This hand-

wheel is collared to the platform as shown. By turning the hand-wheel b in one direction or the other the end c of the lever $d' c$ will be raised or depressed and the end d' contrarily affected, so that the frame $d d' e'$ and the attached presser-beam e are accordingly raised or lowered and made to bear with any required degree of force upon any thickness of material. The knife o , after cutting the layer of cloth, paper, &c., underneath the press-beam, enters 60 into a strip of wood or other suitable material, which is placed in a slot or groove of the plate n . This plate is arranged to be moved horizontally, so that the strip of wood or other material may be moved with the plate n . This 65 movement of the plate is effected by the hand-crank m' of the screw m , which screw passes through a bracket, n' , which projects underneath from the plate n , and which bracket is provided with internal thread corresponding 70 to screw m . This shifting of plate n with its appendix has for its object to offer to the knife o as often as necessary a new part of the face of the strip of wood, for the purpose of cutting all parts of the layer equally smooth. 75

In order to determine the length of samples to be cut, the apparatus is provided, as in ordinary paper-cutting machines, with an angle, p , which may be shifted according to a scale provided for this purpose. 80

I claim—

1. In a sample-cutter, the combination of a knife moved up and down in oblique ways of a presser-beam, E , mounted upon the moving frame $d d' e'$, the fulcrumed lever $d' c$, screw a , 85 and hand-wheel b , for operating said presser-beam, substantially as set forth.

2. In a sample-cutter, the fixed eccentric r , in combination with the movable eccentric-gear on the hand-lever f and with the lever i and link k , connected to the cutter $h o$, all arranged for joint operation, as herein specified.

In testimony whereof I have hereunto set my hand in the presence of two subscribing witnesses.

JOHANN AUGUST HEINRICH MEYER.
